UNITED STATES PATENT OFFICE

FRANK M. SPERLING, OF BRISTOL, PENNSYLVANIA

COPYHOLDER

Application filed June 16, 1932. Serial No. 617,657.

The device which forms the subject matter of this application is an improvement upon the copyholder disclosed in my prior application No. 597,530, filed on the 8th day of March, 1932.

In the present application, there is disclosed novel electro-mechanical means whereby the line-finder will be fed downwardly, step-by-step, by the operation of a switch which may be placed on a typewriting machine, or elsewhere, it being possible to feed the line-finder downwardly by a purely mechanical operation, as distinguished from an electro-mechanical operation, if desired. Divers improvements are proposed in the mechanism whereby the line-finder is carried, and in the mechanism whereby a step-by-step downward movement of the line-finder is rendered possible.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in front elevation, a copyholder embodying the present improvements, parts being broken away;

Fig. 2 is a vertical longitudinal section, wherein many parts are shown in elevation;

Fig. 3 is a vertical longitudinal section, parts appearing in elevation, the observer looking in the direction opposite to that in which he is looking in Fig. 2;

Fig. 4 is a transverse section, at right angles to the table, looking at the electro-magnet, and parts by which the releasing member is mounted and actuated;

Fig. 5 is a top plan of the structure depicted in Fig. 4;

Fig. 6 is a sectional view, illustrating the

electro-magnet and parts associated therewith;

Fig. 7 is a cross section through the guide, looking downwardly toward the lower end of the table;

Fig. 8 is a transverse section illustrating the rack bars and parts associated therewith;

Fig. 9 is a diagrammatic elevation disclosing the rack bars and attendant parts;

Fig. 10 is a fragmental elevation supplementing Fig. 6 in the disclosure of one of the stops.

Fig. 11 is a rear view of the electromagnet and parts associated therewith.

The device forming the subject matter of this application preferably is made of metal throughout.

In defining the relative positions of the parts, the words "right" and "left" will be used under the assumption that the operator is looking at the forward side of the device as in Fig. 1, and not at the back thereof, unless otherwise specified.

The copyholder which gives rise to this application comprises a substantially flat table 1 (Fig. 1) which may be placed as desired.

By preference, however, as shown in Fig. 2, the table 1 has a backward slant. Any suitable means may be provided for supporting the table 1, and large latitude is desired in this respect. It may be expedient to connect angle brackets 2 to the lower part of the table 1, these angle brackets being secured to the upper ring 3 of a support 4, including a lower ring 5, the rings 3 and 5 being connected, as shown at 6 in Fig. 2, in any suitable way, so that the ring 3 and the table 1 which is carried upon it by means of the angular brackets 2, may be adjusted about a substantially vertical axis.

The device may be used with the well-known Morkrum printing machine, which is employed by telegraph companies, railroad companies, and others, although the machine may be used not only by railroad

and telegraph companies, but by public speakers, typists, and others, as well. In the present embodiment of the invention, it has been pre-supposed, without prejudice to any other use, that the article is to be employed in connection with a typewriter 7, one of the

frame bars of which is marked by the numeral 8 in Figs. 1 and 2.

Assuming that messages are to be copied, the messages, ranging from a single message to a thick stack, are supported at their lower ends, on the table 1, by a transverse shelf 9, shown in Fig. 1, and located near to the lower end of the table. The shelf 9 may be vertically adjustable, if desired, that feature being something lying well within the skill of a mechanic and requiring no specific showing in the drawings.

On the upper edge of the table 1 there are upwardly extended brackets 10, to which is secured a transversely extended track 11. A carriage 12 is mounted on the track 11 for sliding movement transversely of the table 1, and is secured in place, for reciprocating movement from right to left and from left to right as shown at 14 in Fig. 2. Near to its right hand end, the carriage 12 has a rearwardly extended shaft 15 (Figs. 2 and 3), on which is journaled a roller 16, mounted to move between the track 11 and an inverted, U-shaped guide 17, carried by the track, the parts 16 and 17 cooperating to steady the carriage 12 for sliding movement along the track 11.

A transversely disposed rack bar 18 is secured to upwardly and rearwardly extended parts 19 of the carriage 12. Bearings 20 are mounted on the rear side of the table 1, and in these bearings, a shaft 21 is journaled for rotation. A pinion 22 is secured to the upper end of the shaft 21 and meshes with the rack bar 18 of the carriage 12. For the rotation of the shaft 21, at the will of an operator, the same is provided at its lower end, below the table 1, with a turning button 23.

Two parallel, upwardly extended posts 24 are mounted at their lower ends on the carriage 12. The upper ends of the posts 24 are connected by a cross piece 25. The cross piece 25 is received within a forwardly extended, U-shaped latch 26 (Fig. 3) which is pivotally mounted intermediate its ends on the cross piece 25, as shown at 27. On the forward end of the latch 26 there is a finger piece 28. A pull spring 29 (Fig. 2) is connected to the cross piece 25 and to the latch 26, behind the fulcrum 27 of the latch, the tendency of the pull spring being to swing the latch 26 to the right in Fig. 1.

A vertically adjustable frame, designated generally by the numeral 30 in Fig. 1, is provided, and includes a headblock 31, which can be slid up and down, at the will of an operator, on the posts 24 of the carriage 12. The frame 30 is slid up and down by means of a handle 32 on the headblock 31. The headblock 31 carries an upwardly extended, bevelled keeper 33, adapted to engage automatically with the spring-actuated latch 26, when the headblock is raised by means of the handle 32, and by means of the

finger piece 28, the latch 26 can be tilted on its fulcrum 27, to disengage the latch 26 from the keeper 33, and then the headblock will slide down the posts 24 on the carriage 12.

The upper end of a guide 34 is rigidly secured to a downwardly extended part 94 of the headblock 31, and the guide extends downwardly along the table 1, in spaced relation thereto. On the lower end of the guide 34, a transverse arm 35 (Fig. 1) is mounted. A first rack bar 36 (Figs. 2 and 3) extends downwardly along the table 1 in parallel relation thereto. Upon one edge, the bar 36 has a rack 37, the teeth of which are spaced widely enough apart to enable the said rack to be used in connection with typewritten matter that is double spaced. On the opposite edge of the bar 36 there is a rack 38, the teeth of which are separated less widely than are the teeth of the rack 37, for single space work. In order that the bar 36 may be turned on its axis, to present either the rack 37 or the rack 38 uppermost, and in operative position, the lower end of the bar 36 is supplied with a knob 40. The lower end portion 95 (Fig. 2) of the bar 36 is cylindrical, and is journaled in the arm 35 on the guide 34, and the upper end 96 (Fig. 3), of the bar 36 is journaled in a laterally offset bearing 39 on the headblock 31.

The first rack bar 36, having the racks 37 and 38 on its opposite edges, is mounted to rotate on its axis, at the will of an operator. Above the first rack bar 36 is located a second rack bar 41 (Fig. 4) having rectangular, downwardly extended teeth 42 (Fig. 3) on its lower edge, the teeth 42 alternating with the teeth 37 or 38 of the first rack bar 36, depending upon whether the teeth 37 or the teeth 38 are disposed uppermost and in operative position. The second rack bar 41 does not turn on its axis, but keeps the position shown in Fig. 2. The upper end of the rack bar 41 is secured to the headblock 31 by means of an angle bracket 43, which is shown best in Fig. 5. The lower end of the rack bar 41 is carried by a post 44 (Fig. 1), and this post is carried (Fig. 2) on the cylindrical lower end 95 of the first rack bar 36, the said cylindrical lower end of the rack bar 36 being mounted to rotate in the post 44. The post 44 is located immediately below the arm 35 that is mounted on the guide 34. A spring tongue 45 is secured to the outer side of the fixed or second rack bar 41, as shown in Figs. 7 and 2. The spring tongue 45 bears against the flat side of the first or rotatable rack bar 36. When the rotatable rack bar 36 is turned on its axis, by means of the knob 40, to present either the rack 38 or the rack 37 of Fig. 3 uppermost, the selected rack will remain in operative position, because the bar 36 is held releasably against turning on its axis,

through the instrumentality of the spring tongue 45.

A slide block 46 is mounted to reciprocate on the guide 34, and on the lower end of the slide block 46 there is a U-shaped extension 47 (Fig. 2), the upper and lower arms of which bear, respectively, on the upper and lower ends of the guide 34 and cause the slide block 46 to move smoothly and evenly on the guide 34. On the upper end of the slide block 46 there is a similar extension 48, having a like purpose.

Figure 10 shows that, in the bottom of the slide block 46, there is a recess 49. An adjusting member 50, in the form of a rod, extends across the recess 49 and has limited adjustment up and down the table 1, that is, in a direction parallel to the guide 34. On the lower end of the adjusting member 50 there is a handle 51, and on the upper end of the adjusting member there is a head 52, in which a line-finder 53 is mounted for longitudinal sliding adjustment, at the will of an operator, transversely of the table 1, as Fig. 1 will show. A spring 54 (Fig. 10) is located in the recess 49 of the slide block 46, and is secured to the slide block. The spring bears on the upper edge of the adjusting member 50. Taking hold of the handle 51, the operator can slide the member 50 of Fig. 10 up and down in the block 46, thereby moving the line-finder 53 of Fig. 1 up or down the table, the line-finder thus being adjusted manually to the position of the line on the paper on the table 1. The spring 54 of Fig. 10 is a friction brake, functioning to hold the line-finder 53 in any position to which it may have been adjusted, as aforesaid.

40. A paper holder 55 extends lengthwise of the table 1 and transversely of the line-finder 53, beneath the line-finder. The upper end of the paper holder 55 is connected, as shown in Fig. 2, to the part 94 of the headblock 31, the lower end of the paper holder being connected to the arm 35 on the guide 34, as Figs. 1 and 7 will make manifest.

The upper end of the slide block 43 (Fig. 1) is located within a U-shaped latch lever 56, fulcrumed intermediate its ends at 57 (Fig. 2) on the slide block. The downward movement of the upper end of the latch lever 56 is limited by a stop 58 on the slide block. In the upper end of the latch lever 56 is secured a transverse finger 59, which as shown in Fig. 8, is of angular form. The transverse finger 59 has a thinned end 60 (Fig. 9) which, when the lever 56 is swung up and down on its fulcrum 57, moves up and down between the teeth of the single space rack 38 on the first or rotatable rack bar 36 and the teeth 42 of the second or fixed rack bar 41: or between the teeth 42 of the rack bar 41 and the teeth 37 of the rack bar

36, if the teeth 37 are uppermost, for double spacing.

A laterally offset shaft 61 (Fig. 1) extends lengthwise of the table 1, across and above the finger 59 (Fig. 8) of the lever 56, inwardly of the thinned end 60 of the finger. It is shown in Fig. 7 that the lower end of the shaft 61 is mounted to rock in the post 44 of Fig. 2. Referring to Fig. 3, the upper end of the shaft 61 is journaled in the bracket 43 which connects the rack bar 41 to the headblock 31. Throughout the major portion of its length, the shaft 61 is parallel to the second rack bar 41, the guide 34 and the paper holder 55, as Fig. 1 will show.

A releasing member 62 extends lengthwise of the table 1 (Fig. 1) and is located underneath the finger 59 (Fig. 8) that is carried by the latch lever 56. At its lower end, the releasing member 62 has a laterally offset arm 63 (Fig. 7) which is pivoted to the transverse member 35 (Fig. 1) on the guide 34. The arm 63 of the releasing member 62 has a laterally extended finger piece 64, shown in Fig. 1, and employed to operate the releasing member manually, although the releasing member generally is actuated by an electro-mechanical means connected to the typewriter frame bar 8, and described hereinafter.

Secured to the upper end of the releasing member 62 is a hanger 65 which is U-shaped in top plan (Fig. 5). The upper arm 66 of the hanger 65, is, in substance, an arm on the releasing member 62, like the lower arm 63 of Fig. 7. The arm 66 is pivoted at 67 (Fig. 4) on the headblock 31. The lower arm 69 of the hanger 65 on the releasing member 62 has a notch 70 (Figs. 4 and 1) that receives the crank or offset portion of the shaft 61. A

pull spring 71 is connected to the lower part of the hanger 65, below the pivotal mounting 67 of the hanger, and to a part 72 of the paper holder 55. An angular stop 97 (Figs 5 and 11) is secured to the upper or back side of the arm 66 of the releasing member 62, and has a rearwardly-extended end 98, located above and about parallel to the upper surface of the headblock 31, the end 98 of the stop working beneath a guard 99, superposed on the bracket 43 and secured, with the bracket, to the head-block 31. Noting the arrows in Fig. 11 and the pull spring 71 of Fig. 4, it will be clear that as the spring 71 tilts the upper end of the hanger 65 to the right in Fig. 4, on the fulcrum 67, to lower the releasing member 62, the end 98 of the stop 97 will engage the upper surface of the headblock 31, and terminate the movement of the hanger 65 and the releasing member 62. Noting the electro-magnet 74 of Figs. 4 and 5, to which the hanger 65 is responsive, as hereinafter explained, it will be understood that as the electro-magnet causes the upper end of the hanger 65 to swing to the left in Fig. 4, the end 98 of the stop 97 will engage the upper surface of the

headblock 31 and terminate the movement of the hanger and the releasing member.

- It is shown in Fig. 5 that an armature 73 is mounted on the upper arm 66 of the hanger 65 and is insulated therefrom. The armature 73 is responsive to the aforesaid electro-magnet 74, which is mounted on the headblock 31. The ends of the winding 75 (Fig. 1) of the electro-magnet 74 are connected to spring tongues 76 carried by brackets 77 on the headblock 31, the tongues 76 being insulated from the brackets. The spring tongues 76 bear against conducting standards 78, mounted on the carriage 12, but insulated therefrom. To the upper ends of the standards 78 are joined conductors 79 leading to a normally open electrical switch 80, mounted removably, by means of a hook 100, or otherwise, on the frame bar 8 of the typewriter 7. The specific construction of the switch 80 need not be described in detail, since there are many switches adapted for this purpose, it being sufficient to state that the switch 80 includes a push button 81, located conveniently adjacent to the typewriter 7 or other instrumentality wherewith the device forming the subject matter of this application is used.
- In practical operation, the papers to be copied are supported on the table 1 and on the shelf 9, and are held down, near to the right hand margin, by the paper holder 55. The line-finder 53 is under the line of matter which is being copied, and casts no shadow. The paper holder 55 can be adjusted readily, to the left or to the right, so as to hold down the papers, and at the same time obscure little or none of the text. The adjustment of the paper holder 55, to the right or to the left, is brought about by turning the button 23 of Fig. 1, the shaft 21 being rotated, and the pinion 22 on the shaft cooperating with the rack bar 18 of the carriage 12, to move the carriage to the left or to the right. When the carriage 12 is moved transversely of the table 1, the frame 30 (which includes the paper holder 55) is moved laterally, also, because the headblock 31 of the frame 30 is carried by the posts 24 of the carriage 12, as the carriage slides on the track 11. The frame 30 may be adjusted vertically, through the medium of the handle 32 on the headblock 31, because the headblock 31 of the frame can slide vertically on the posts 24 of the carriage 12. This vertical adjustment of the frame 30 and of the paper holder 55 of course enables the paper holder to cooperate with the stack of papers on the table 1, regardless of the height of the stack. The headblock 31, and parts carried thereby, are heavy enough to cause the paper holder 55 to have a firm pressure on the stack of papers.

When the frame 30 is elevated by the handle 32, as the headblock 31 slides upwardly on the post 24 of the carriage 12, the beveled keeper 33 on the headblock engages automati-

cally with the latch 26 that is pivoted at 27 on the cross piece 25 and is actuated by the spring 29. The latch 26 may be swung manually by means of the finger piece 28, to disengage the latch 26 from the keeper 33 and let the frame 30 slide downwardly on the posts 24 of the carriage 12, to the position of Figs. 1 and 3.

As to the up and down transverse adjustment of the line-finder 53, relatively to the slide block 46, as distinguished from the movement brought about when the block 46 is slid bodily along the guide bar 34, it will be clear, when Figs. 10 and 2 are compared, that all that the operator has to do is to move the member 50 (which carries the line-finder 53) up or down in the slide block 46, the said member being frictionally held in its adjusted position by the spring 54.

By means of the knob 40, the second rack bar 41 may be reversed on its axis, to bring either the rack 38 or the rack 37 of Fig. 3 uppermost, depending upon whether the matter to be copied is single spaced or double spaced.

Referring, first, to the operation of the latch lever 56 of Fig. 3, in conjunction with Fig. 8, and disregarding for the moment the remote control of the latch lever, it will be clear that as the upper end of the latch lever 56 is raised, the thinned outer end 60 of the finger 59 on the latch lever will move out of the rack 38 on the bar 36 (Fig. 9), into engagement with the teeth 42 of the rack bar 41: and when the upper end of the latch lever 56 in Fig. 3 moves downwardly, the thinned end 60 of the finger 59 will engage with the next lower tooth 38 of the rack bar 36, the slide block 46 moving downwardly one step along the guide 34, and the line-finder 53 being carried downwardly one step, accordingly.

In the preceding paragraph, reference has been made to the remote control of the latch lever 56 and the finger 59 of the latch lever. There are two remote controls, one being purely mechanical, and the other being electro-mechanical. The purely mechanical control will be discussed first, not because it is of primary importance, but because it is the simpler of the two, and forms a basis from which the description of the operation of the electro-mechanical control can be built up.

Referring to Fig. 1, and noting the finger piece 64 on the arm 63 (Fig. 7) of the releasing member 62 (Fig. 8), it will be understood that when the finger piece 64 is pressed downwardly, the releasing member 62 will be raised, the releasing member swinging upwardly on its pivotal connection 64 (Fig. 7) with the arm 35 at the lower end of the guide 34, and on the pivotal connection 67 (Fig. 1) between the hanger 65 and the slide block 31, it being recalled that the hanger 65 is, in substance, an offset arm on the releasing mem-

ber 62, resembling the lower arm 63 (Fig. 7) of the releasing member.

As the releasing member 62 (Fig. 8) moves upwardly, it raises the thinned end 60 of the finger 59 out of engagement with the rack 38 of the bar 36, the lever 56 (Fig. 3), which carries the finger 59, being tilted on its fulcrum connection 57 with the slide block 46. The crank-like or offset shaft 61, being located above the finger 59, serves to keep the end 60 of the finger 59 engaged with the rack 38 of the bar 36, but when the releasing member 62 is raised as aforesaid, the shaft or holding member 61 will be raised also, permitting the end 60 of the finger 59 to rise out of the rack 38 on the bar 36. The raising of the holding member 61 is brought about by the lower arm 69 of the hanger 65, the offset part of the shaft 61 being received slidably in the notch 70 of the arm 69. The hanger 65, including the part 69 is, in substance, an arm on the upper end of the releasing member 62, and resembling, in broad function, the arm 63 shown on the lower end of the releasing member 62 in Fig. 7. As the hanger 65 and its arm 69 swing upwardly, on the pivotal connection 67 (Fig. 1) between the hanger and the headblock 31, the holding member 61 of Fig. 8 will be raised at the same time that the releasing member 62 is raised to release the part 60 of the finger 59 from the rack 38 on the bar 36. When the operator relieves the pressure on the finger piece 64 of Fig. 1, the parts will resume the position of Fig. 8, under the pull of the spring 71 of Fig. 4, the said spring being connected to the hanger 65 that carries the upper end of the releasing member 62, and to the bracket 72 on the headblock 31.

The description above concluded relates to the purely mechanical control of the step-by-step downward movement of the slide block 56 and the line-finder 53. Passing to the electro-mechanical control, it will be observed that when the operator closes the switch 80 on the frame 8 of the typewriting machine 7, by means of the push button 81 of Figs. 1 and 2, an electrical circuit through the winding 77 of the electromagnet 74 is closed, the magnet is energized, the armature 73 on the hanger 65 (which carries the releasing member 62) is attracted by the magnet 74, and the same operation takes place as occurs when the parts are actuated by the finger piece 64. A comparison of the finger piece 64 and the armature 73 in Fig. 1 will indicate at a glance, their similarity in function.

The circuit that is closed by the push button 81 of the switch 80 includes the conductors 79, the standards 78 on the carriage 12, the spring tongues 76 on the brackets 77 of the headblock 31, and the winding 75 of the electro-magnet 74. It will be observed that the push button 81 of the switch 80 is located closely adjacent to the keys of the typewriter

7, and can be operated as easily as any of the standard typewriter keys, or the spacing bar of the typewriter.

What is claimed is:

1. In a device of the class described, a paper-holding table, a gravity-actuated slide, means for mounting the slide for movement downwardly along the table, a line-finder carried by the slide, mechanism for limiting the downward movement of the slide and the line-finder to a step-by-step progression, said mechanism including a movable actuating part for said mechanism, electro-mechanical means for operating said actuating part, and a device for controlling the electro-mechanical means from a remote point.

2. A device of the class described, constructed as set forth in claim 1, and further characterized by the fact that the electro-mechanical means comprises an electro-magnet supported from the table, an armature on said movable actuating part and responsive to the electro-magnet, a circuit including the winding of the electro-magnet, and said device being a switch interposed in said circuit.

3. In a device of the class described, a table, a gravity-actuated slide, means for mounting the slide for movement downwardly along the table, a line-finder carried by the slide, a rack supported by the table, a latch cooperating with the rack to limit the downward movement of the slide and the line-finder to a step-by-step progression, means for mounting the latch movably on the slide, cooperating parts including a member holding the latch engaged with the rack and a member engaging the latch to disengage the latch from the rack, means for supporting said cooperating parts movably with respect to the table, interengaging elements on said cooperating parts for moving them in synchronism when one of them is actuated, and means for actuating one of said cooperating parts.

4. A device of the class described, constructed as set forth in claim 3, and further characterized by the fact that the last specified means embodies an electro-magnet supported adjacent to the table, and an armature on one of said cooperating parts, the armature being responsive to the electro-magnet.

5. In a device of the class described, a table, a gravity-actuated slide, means for mounting the slide for movement downwardly along the table, a line-finder carried by the slide, a rack supported by the table, a latch cooperating with the rack to limit the downward movement of the slide and the line-finder to a step-by-step progression, means for mounting the latch movably on the slide, a pair of shafts having cranks located on opposite sides of the latch, the

slide being movable to move the latch between the cranks, longitudinally of the shafts, means for mounting the shafts for rocking movement, means for connecting the shafts operatively together, and means for operating one shaft.

6. A device of the class described, constructed as set forth in claim 5, and further characterized by the fact that the means for connecting the shafts operatively together is a transverse arm on one shaft, the arm being engaged with the crank of the other shaft.

7. In a device of the class described, a table, a guide extended along the table, a slide mounted to reciprocate upon the guide, means for controlling the movement of the slide, a line-finder, and means for mounting the line-finder on the slide for adjustment with respect to the slide, transversely of the line-finder, and longitudinally of the guide.

8. In a device of the class described, a table, a guide extended along the table, a slide mounted to reciprocate upon the guide, 25 means for controlling the movement of the slide, an operating member movable in the slide, at the will of an operator, in a direction substantially parallel to the guide, a line-finder disposed transversely of the guide and carried by the operating member, and means for holding the operating member in adjusted positions with respect to the slide.

9. In a device of the class described, a table, a carriage movable transversely of the table, 35 means for moving the carriage transversely of the table, a headblock, means for mounting the headblock for vertical movement on the carriage, a slide, means for mounting the slide on the headblock for movement with respect to the table, a line-finder carried by the slide, a rack carried by the headblock, a latch movably mounted on the slide and cooperating with the rack to limit the movement of the slide to a step-by-step progression, a shaft including a crank portion engaged with the latch to disengage the latch from the rack, the shaft including arms, one of which is pivoted to the headblock, the other of which is pivoted to the means for mounting the slide, means for 45 rocking the shaft, and a stop carried by the first specified one of said arms and engaging the headblock to limit the movement of the shaft.

10. A device of the class described constructed as set forth in claim 9 and further characterized by the fact that the means for 55 rocking the shaft embodies an armature on said one of the arms, and an electro-magnet on the headblock, the armature being responsive to the electro-magnet.

11. A device of the class described comprising a table, a carriage movable transversely of the table, means for moving the carriage transversely of the table, posts mounted on 65 the carriage, a headblock slidable vertically

on the posts, a keeper carried by the headblock, a cross piece connecting the posts, a latch movably mounted on the cross piece, spring means for operating the latch to hold it in the path of the keeper, when the headblock is moved upwardly on the posts, a line-finder cooperating with the table, and means for mounting the line-finder on the headblock.

12. In a device of the class described, a table, a slide, means for supporting the slide for movement with respect to the table, a line-finder carried by the slide and cooperating with the table, a latch movably mounted on the slide, a first rack located below the latch and having lines of teeth, the teeth of the lines being differently spaced, means for mounting the first rack for axial rotation, to present either line of teeth to the latch, a second rack and means for mounting the second rack above the latch, the second rack having teeth which alternate with the teeth of both lines on the first rack, and means under the control of an operator for actuating the latch to cause the latch to move between the teeth of the selected line on the first rack and the teeth of the second rack.

13. In a device of the class described, a table, a gravity operated, releasable line-finder, means for mounting the line-finder for movement with respect to the table, mechanism for constraining the movement of the line-finder to a step-by-step movement, when the line-finder is released, and an electro-mechanical means accessible from a remote point and under the control of an operator for releasing the line-finder.

In testimony that I claim the foregoing as my own, I have hereto affixed my signature.

FRANK M. SPERLING.
